UNITED STATES PATENT OFFICE.

WILLIAM F. DEISTER, OF FORT WAYNE, INDIANA, ASSIGNOR TO DEISTER MACHINE COMPANY, OF FORT WAYNE, INDIANA, A CORPORATION OF INDIANA.

MECHANISM FOR OPERATING CONCENTRATING UNITS.

1,088,683.

Specification of Letters Patent.

Patented Mar. 3, 1914.

Application filed July 30, 1913. Serial No. 782,084.

To all whom it may concern:

Be it known that I, WILLIAM F. DEISTER, residing at Fort Wayne, in the county of Allen and State of Indiana, a citizen of the 5 United States, have invented or discovered certain new and useful Improvements in Mechanism for Operating Concentrating Units, of which improvements the following is a specification.

10 The invention described herein relates to certain improvements in the operation of a battery of concentrating units, each unit consisting of a plurality of independently pivoted superposed decks, such as form the 15 subject-matter of Letters Patent Nos. 1,007,074 and 1,007,075, dated October 31, 1911. As stated in said patents, the material to be treated, as slime, is caused to flow slowly and in thin streams from end to 20 end of said decks, when in an inclined position. The decks are then inclined in the opposite direction and the values deposited on their surfaces washed off, when the decks are returned to feed position and the 25 scribed operations repeated.

The invention described herein has for its object to provide for the successive operation of a plurality of such units by a common uniformly operated member and to effect the described movements of the decks of each unit in such manner as to insure the proper duration of the feeding and washing periods.

The invention is hereinafter more fully 35 described and claimed.

In the accompanying drawings forming a part of this specification, Figure 1 is a side elevation of a concentrating unit in combination with an element or section of 40 the battery operating mechanism; Figs. 2 and 4 are edge and side elevations respectively of an element of the common operating mechanism; Fig. 3 is a detail view of a portion of the mechanism shown in Figs. 2 45 and 4, and Fig. 5 is a view similar to Fig. 1, illustrating a modification in the relative arrangement of the decks and the operating mechanism, and Fig. 6 is a diagrammatic view illustrating a battery of concentrating 50 units.

In the practice of my invention, each unit of the battery is constructed substantially as described and shown in the patents referred to and consists of a series of superposed decks 1 so pivotally supported as to

be capable of movement from one inclined position in which the material to be treated will flow slowly down along its surface to an opposite and sharper inclination to permit of the accumulated values being washed off by a rapid flow of water. As fully disclosed in said patents provision is made for automatically controlling by the decks as they move from one position to the other the flow of material and water onto the decks in accordance with the position of the decks.

While not necessary, it is preferred that the decks should have their pivotal points so located that the decks have a constant 70 bias to move from washing to feed position and hence the improvement is shown and described in connection with decks so supported, but as regards the broad statements or claims, the invention is not limited to 75 such construction.

As will be seen by reference to Fig. 6, the concentrating units A, B, C, D, are preferably arranged side by side, so that the slime and washing water can be supplied to the 80 decks of the several units by troughs 2. The tailings are discharged into a launder 4 and the values into a launder (not shown) below the slime launder 2. The deck operating and controlling units are preferably 85 operated by a common shaft 5 extending the length of the battery and driven by any suitable means as a motor 6.

As clearly shown in Fig. 1, the several decks are flexibly tied together so as to 90 move in unison by straps 7, and turn buckles 8 have their respective ends loosely connected to the lowest deck and the ends of a walking beam 9. This beam is secured midway of its length to a shaft 10, which is 95 mounted in suitable bearings with its axis coincident with a vertical plane passing through the pivotal axes of the decks. The walking beam is oscillated to shift the decks by an arm 11 extending down into operative relation to the cam 12 on the driven shaft 5. The lower end of the arm 11 is provided with a part or member 13 (preferably made in the form of a roller) laterally movable into and out of the plane of rotation 100 of the cam. As shown in Figs. 2 and 4 this roller is provided with a short shaft 14 loosely mounted in bearings on the end of the arm 11, and is adapted to be shifted into the 105 plane of rotation of the cam by a spring 15. 110

and out of such plane by a rib 16 extending at an angle across the face of the cam.

A suitable lock is provided for holding the roller out of alignment with the cam during the time slime is being fed onto the decks. A convenient form of lock consists of a finger 17 carried by a slide 18 and adapted to be forced by the spring 19 into a peripheral groove 20 in the shaft 14 when the latter has been shifted by the rib 16. The slide is mounted in suitable bearings on the arm 11 and is provided with a shoe 21 which is engaged to raise the slide and unlock 14 by an arm 22 on the counter-shaft 23. This counter-shaft is driven through a worm gearing 24 by the main shaft 5, such gearing being so designed as to impart one complete rotation to the counter-shaft carrying the unlocking arm 22 for any desired number of rotations of the shaft 5 and cam 12. As the decks are in feed position while the roller 13 is out of alignment with the cam, the number of rotations of the shaft 5 to one rotation of the unlocking arm, will be dependent upon the number of revolutions per minute of the shaft and the desired duration of feed.

In lieu of arranging the power shaft 5 and the deck shifting mechanisms in line vertically with the pivotal axes of the decks as shown in Fig. 1, they may be arranged at one side of the plane of such axes as shown in Fig. 5.

In describing the operation of my improvement it will be supposed that the cam is moving in the direction of the arrows *a*, Figs. 1, 2 and 3, and the slime feeding period is terminating. As the unlocking arm 22 continues its movement in the direction of the arrow *b*, it will raise the slide 18 interlocking the shaft 14, which will then be shifted by springs 15 moving the roller 13 into the plane of rotation of the cam. The advancing shoulder *c* on the cam will engage the deck shifting arm 11 and push it to the left in Fig. 1 and thereby shift the decks from feed to washing position. While the portion of the cam between the shoulder *c* and the point *d* is in engagement with the arm 11, the decks will be held in washing position. When the point *d* reaches the arm, the decks which as stated have a bias to move from washing to feed position, will begin their return movement. The portion of the cam between point *d* and the rib 16 is so constructed that the rate of the return movement will progressively increase until the roller 13 is shifted laterally by the rib 16 when the decks will be free to complete the return to feed position. At the beginning of the return movement the washing water is cut off as shown and described in the patents referred to, and opportunity is afforded while the portion of the cam between point *d* and the rib 16 is in engagement

with rollers 13 for the washing water with the valves to drain off of the surfaces of the decks.

It will be understood that by properly setting cams on the shaft 5, the relative operations of the units can be varied as desired, so that such units may operate in any desired sequence or simultaneously.

As the slime to be treated may vary in richness from time to time and as the duration of the feeding period is dependent on the richness of the slime, the feed period can be lengthened or shortened by changing the relative rate of rotation of the shafts 5 and 23. And in lieu of feeding all the units of the battery from a common launder, they may be independently supplied, and in case the slime fed to some of the units is richer than that fed to others, the feed period of such unit can be shortened without affecting the operation of the other units. By merely removing the shoe 21 any one of the units can be put out of operation when desired.

I claim herein as my invention:

1. In a concentrating plant, the combination of a battery consisting of a plurality of concentrating units, each consisting of a plurality of pivotally mounted decks, a plurality of means for reversing the inclination of the decks of the several units, continuously operating means for the operation of the deck reversing means and variable means for connecting each of the operating means.

2. In a concentrating plant, the combination of a plurality of concentrating units, each consisting of a plurality of pivotally mounted decks, a plurality of means for reversing the inclination of the decks, and continuously operating means for operating the deck reversing means and means for controlling the relative periodicities of such reversals.

3. In a concentrating plant, the combination of a plurality of concentrating units, each consisting of a plurality of pivotally mounted decks, a plurality of means for reversing the inclination of the decks, and continuously operating means for operating the deck reversing means and adapted to impart different feed periodicities to different units.

4. In a concentrating plant, the combination of a plurality of concentrating units, each consisting of a plurality of pivotally mounted decks, a plurality of means for reversing the inclination of the decks, a driven shaft extending along the line of units, and adjustable means for automatically connecting each reversing means with said shaft.

5. In a concentrating plant, the combination of a plurality of concentrating units, each consisting of a plurality of pivotally mounted decks, a plurality of means for reversing the inclination of the decks, a driven

- shaft extending along the line of units, and independent and adjustable means for automatically connecting each reversing means with said shaft.
6. In a concentrating plant, the combination of a plurality of concentrating units, each consisting of a plurality of decks so pivotally mounted as to have a bias to feed position, a plurality of means for shifting the decks from feed position to washing position and controlling the return to feed position, a driven shaft, and automatically operating and adjustable means for connecting each reversing means with the shaft.
10. 7. The combination of a concentrating unit, consisting of a plurality of decks so pivotally mounted as to have a bias to move to feed position, an arm connected to the decks, a rotating cam for shifting said arm, and means moving in timed relation to the cam for changing the operative relation of the arm and cam.
8. The combination of a concentrating unit, consisting of a plurality of decks so pivotally mounted as to have a bias to move to feed position, an arm connected to the decks, a continuously rotating shaft, a cam carried by the shaft for shifting said arm, and means operated by the shaft for changing the operative relations of the cam and arm.
15. In testimony whereof, I have hereunto set my hand.

WILLIAM F. DEISTER.
